UNITED STATES PATENT OFFICE.

JOHN W. PAGE, OF CHICAGO, ILLINOIS.

EXCAVATING DEVICE.

1,194,777.

Specification of Letters Patent. Patented Aug. 15, 1916.

Application filed August 11, 1912. Serial No. 784,238.

To all whom it may concern:

Be it known that I, JOHN W. PAGE, a citizen of the United States, residing at Chicago, in the county of Cook and State of Illinois, have invented a new and useful Improvement in Excavating Devices, of which the following is a specification.

My invention relates to certain new and useful improvements in excavating devices, and is fully described and explained in the specification and shown in the accompanying drawings, in which:—

Figure 1 is an elevation of one end of my improved device in use, showing the bucket in dumping position; Fig. 2 is a similar view of the opposite end showing, in dotted lines, the bucket in digging position; Fig. 3 is a side elevation of a bucket, and Fig. 4 is a top plan of the trolley.

Referring to the drawings, 5 is a cable-way provided with the usual means whereby it may be tightened and slackened. Upon this cable-way is a trolley in the preferred form consisting of two parts, 6 and 7, pivoted together and carrying rollers or wheels 8 running upon the cable-way. Pivoted to the trolley is a bail 9, to which is swiveled an excavating shovel 10, the point of the pivot preferably being behind the center of gravity of said shovel.

11 is the hauling-line of the bucket, 12 is the holding-line thereof, and 13 is the loading-line to which both the holding and hauling lines are attached, as is common practice with the Page buckets now used for excavating purposes. In the particular example here shown, the holding-line 12 runs over a sheave 14 at the front end of the bucket and thence back to the sheave 15 carried by the bail. By this means a double purchase is obtained between the sheave and the forward end of the bucket, this being an expedient frequently adopted in the use of the Page bucket.

It will be evident from the drawings that the inclination of the cable-way is such that the bucket will run down to the point at which it is sought to have it work, and therefore no mechanism for hauling it in a backward direction is required in this particular instance. It will also be evident to those skilled in the art that since there is no novelty in hanging a Page bucket on a cable-way, the parts heretofore described may be assumed to be old.

The novelty in the present case lies in the

means whereby the bucket is dumped automatically, and this is best shown in Fig. 3. 16 is a sheave carried preferably at the junction of the hauling, holding and loading lines. A rope 17 connected to the trolley runs under the sheave 16 and up to another sheave 18 which runs on the cable-way. 19 is a stop-block fast on the cable-way at the point where the dumping is to occur. As the bucket is drawn forward, the sheave 18 strikes this block 19 and is pushed back toward the trolley, thus shortening the bight in the rope 17 and drawing backward the sheave 16. The result is that both the holding and hauling lines are slackened and the front of the bucket descends in an obvious manner. Thus the bucket is always automatically dumped at the proper point.

The present device has been found particularly useful in excavating gravel-pits and for similar purposes where it is sought to dump the material from many successive bucket loads in a predetermined position, as in the hopper shown in Fig. 1. The bucket takes its load in the usual way and is simply pulled forward by the machine until it automatically dumps. Then, by paying out the loading-line, the bucket returns to the position where the operation can be repeated.

I realize that considerable variation is possible in the details of the construction herein shown, and I do not intend to limit myself thereto, except as pointed out in the following claims, in which it is my intention to claim all the novelty inherent in the device as broadly as is permitted by the state of the art.

I claim as new and desire to secure by Letters Patent:—

1. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity for pulling the bucket along said main cable, and means operated by continuous forward movement of said hauling-line for permitting said bucket to swing on its pivot to dumping position during said continuous forward movement of said hauling-line.

2. In apparatus of the character set forth, the combination of a main cable, a carriage movable thereon, a scraper-bucket pivotally

mounted on said carriage in the rear of the center of gravity of the bucket when loaded, a hauling-line connected with said bucket in advance of its center of gravity for pulling said bucket along said main cable, and means engaging said hauling-line in advance of said bucket operating at a predetermined point to accelerate the movement of said carriage along said main cable relative to the movement of said hauling-line, for the purpose set forth.

3. In apparatus of the character set forth, the combination of a main cable, a carriage movable thereon, a scraper-bucket pivotally mounted on said carriage in the rear of the center of gravity of the bucket when loaded, a hauling-line connected with said bucket in advance of its center of gravity for pulling the bucket along said main cable, a block running on said main cable, a stop on said cable in the path of movement of said block, and a cable connected with said block and carriage and operatively engaging said hauling-line, for the purpose set forth.

4. In apparatus of the character set forth, the combination of a main cable, a carriage movable thereon, a scraper-bucket pivotally mounted on said carriage in the rear of the center of gravity of the bucket when loaded, a hauling-line for pulling the bucket along

said main cable, formed of sections connected with said bucket in advance of its center of gravity, one of said sections extending in engagement with said carriage, and means operated by continuous forward movement of said hauling-line for permitting said hauling-line sections to become slackened.

5. In apparatus of the character set forth, the combination of a main cable, a carriage movable thereon, a scraper-bucket pivotally mounted on said carriage in the rear of the center of gravity of the bucket when loaded, a hauling-line for pulling the bucket along said main cable, formed of sections connected with said bucket in advance of its center of gravity, one of said sections extending in engagement with said carriage, a block running on said main cable, a stop on said cable in the path of movement of said block, and a cable connecting said block and carriage and operatively engaging said hauling-line, for the purpose set forth.

In testimony whereof I have hereunto set my hand this 31st day of July, 1913.

JOHN W. PAGE.
